UNITED STATES PATENT OFFICE.

GOODWIN B. SMITH AND IRA ROBBINS, OF PHILADELPHIA, PENNSYLVANIA.

STAMP-AFFIXER.

No. 902,179.

Specification of Letters Patent.

Patented Oct. 27, 1906.

Application filed December 6, 1906. Serial No. 346,635.

To all whom it may concern:

Be it known that we, GOODWIN B. SMITH and IRA ROBBINS, citizens of the United States, residing at Philadelphia, in the county 5 of Philadelphia and State of Pennsylvania, have invented certain new and useful Improvements in Stamp-Affixers, of which the following is a specification.

Our invention relates to an improved 10 portable hand stamp or label affixing machine and has for its object the provision of an improved device of this character comprising mechanism for feeding the stamps or labels from a roll; means for moistening or 15 mucilaging said stamps and means for pressing said stamps into engagement with the object to which the stamp is to be affixed.

A further object of the invention is the provision of an improved magazine for a machine 20 of this character constructed in such manner that said magazine may only be opened by an authorized person possessing a key.

A further object of the invention is the provision 25 of an improved cutting mechanism comprising a fixed cutting knife and a movable cutting knife, one of said knives being yieldingly mounted with relation to the other.

A further object of the invention is the provision 30 of a vertically movable plunger having a head mounted upon a universal joint.

Further objects and advantages of the invention will be set forth in the detailed description which now follows:

In the accompanying drawings: Figure 1 is a side elevation of a portable hand stamp or label affixer constructed in accordance with the invention. Fig. 2 is a vertical section 40 of the machine. Fig. 3 is a transverse vertical section upon line $x-x$ of Fig. 2. Fig. 4 is a detail plan view of the feeding and moistening rollers and the moistening receptacle upon which they are mounted. Fig. 5 is a horizontal section upon line $y-y$ of Fig. 2. Fig. 6 is a detail view of a ratchet hereinafter described. Fig. 7 is a horizontal section through said ratchet, and Fig. 8 is a detail view of a cross-head hereinafter described.

Like numerals designate corresponding parts in all of the figures of the drawing.

Referring to the drawing, the numeral 5 designates the base of the machine. Extending from this base are the vertical mem-

bers 6 of the frame, said vertical members 55 having ways 7 formed therein. Slidably disposed in these ways for vertical movement, is a cross head 8, said cross head being carried upon the lower end of a hollow rod 9. A handle 10 is threaded upon the upper end of 60 this hollow rod. A spring 11 bears at its lower end against a washer 12 and at its upper end against a plug 13, the head of said plug bearing against the underside of the handle 10. The washer 12 is supported by a 65 pin 14 which passes through the boss 15 of the frame. As is clearly illustrated in Fig. 2, the hollow rod 9 is slidably disposed in this boss and the cross head 8 which is carried upon the lower end of the rod, is mounted for 70 slidable movement, as has been before stated, in the ways 7. The hollow rod 9 is slotted as at 16, the pin 14 passing through these slots. A knife 17 is mounted upon forwardly extending members 18, said members being in 75 turn pivotally mounted upon a pin 19 carried by the cross head 8. A rod 21 passes through an opening 22 of the depending lower end of the hollow rod 9 and has an enlarged head 24 which bears against the knife. A spring 23 80 bears between the depending lower end of the rod 9 and said enlarged head 24 of this pin. A nut 25 is threaded upon the outer end of the bolt to provide means for adjusting said bolt, as will be hereinafter set forth. 85 The depending lower end of the hollow rod 9 is provided with a ball head 26. Screws 27 secure a presser head 28 upon the ball head 26, said screws passing through the presser head and entering plates 29 which engage the 90 reduced neck 30 of the ball head.

The base 5 has a dove-tailed recess 31 formed therein for the reception of a receptacle 32 (see Fig. 3). This receptacle after having been placed in position may be locked 95 against accidental movement by a set screw 34 which is threaded into a lug 35 of the base 5. Fast upon a shaft 36 which passes transversely through this receptacle is a moistening or mucilaging roll 37, while fast upon the 100 outer end of said shaft is a pinion 38. This moistening or mucilaging roll has a series of grooves 39 formed therein for the reception of the member 40 of a cap plate 41. A plate 42 has resilient fingers 43 which extend over 105 the cap plate 41 and overlie the front edge of the receptacle 32 and serve a purpose which will be hereinafter set forth. A sponge 44 is

adapted to moisten the roll 37 if stamps are gummed, said roll in turn moistening the stamps as will be hereinafter described and if the stamps are not gummed, mucilage or other similar material is put in the receptacle 32. The side members 45 are pivoted in ears 46 of the receptacle 32 by means of a rod 47 which passes through said side members and into said ears. A feed roll 48 is mounted upon a shaft 49, said shaft being in turn mounted in the upper ends of arms 50, the inner ends of said arms being pivoted as at 51 to the ears 46. A guide rod 52 is carried by the side members 45 as will be hereinafter described. When the arms 50 are swung over to the position illustrated in Fig. 2, pins 53 rest in recesses 54 formed in the side members 45. At this time a pinion 55 which is mounted upon the shaft 49, meshes with the pinion 38 of the shaft 36. It is preferred that the shafts 49 and 36 be readily removable. To this end said shafts are inserted loosely in their bearings, and are held from displacement by the friction between the pinions 45 and 38 and the associated parts. In disassembling the parts when it is desired to remove the pinions 55 and 38, the respective shafts 49 and 36 are given a slight axial blow which displaces them in an endwise direction.

Referring particularly to Fig. 2, it will be seen that a guide bar 56 is arranged across the front of the receptacle and that the stamps indicated at 57 pass beneath said guide bar. Secured by a screw 58 to the front wall of the receptacle, is a knife 59 having a cutting edge 60 with which the cutting edge of the knife 17 is adapted to co-act. Upon each side of the receptacle 32, the knife 59 has an upwardly extending portion 61 having its outer face slightly beveled as at 62 for a purpose which will be hereinafter described. When the receptacle 32 is slid into position in the dove-tailed ways 31, the free end of a spring 63 overlies the end of the arm 50 to hold the feed roller firmly into engagement with the stamps. A spool 64 is mounted upon a pintle 65, said pintle projecting from the side wall 66 of a casing 67. This pintle projects through the wall 66 and has a nut 68 threaded upon its outer end, said pintle being adapted to be detachably received in a bifurcated portion 69 of an extension 70 of the frame 6, whereby, when the nut 68 is loosened the casing 67 with its associated parts may be removed as an entirety.

The stamps 57 are wound upon the spool 64, are then threaded beneath the rod 52, between the rollers 48 and 37 beneath the guide bar 56 and over the cutting edge 60 of the knife 59. As is best illustrated in Figs. 3 and 5 one side of the casing 67 is closed by a removable plate 71 which has a central opening 72 formed therethrough for the reception of the end of the pintle 65, and which has an

annular flange 73 which enters the casing 67. A locking pin 74 is carried by the plate 75, said plate being secured to the plate 73. This locking pin enters channel 76 of a lug 77 which is secured to the bottom of the casing 67. The locking pin 74 is recessed as at 78 for the reception of the free end of a spring tongue 79. When the cap plate is placed in position, the head 80 of the locking pin 74 snaps behind the spring tongue to prevent the removal of the cap plate 73 and to consequently prevent the removal of the stamps. When it is desired to refill the magazine formed by the casing 67 and the parts carried thereby, a properly authorized person provided with a key 81, may, by inserting said key in the key hole channel 82, which lies parallel with the channel 76, lift the spring tongue 79 by turning said key to cause the ward of said key to engage said spring tongue, as is clearly illustrated in Fig. 5.

It is of course apparent that some means must be provided for intermittently feeding the stamps forward and the mechanism for doing this will now be described. By referring to Fig. 7, it will be seen that a stub shaft 83 is carried by the extension 70 of the frame. Mounted upon the stub shaft is a gear wheel 84 which has its face recessed as shown in Fig. 7. A ratchet 86 which is cut away as at 87, 88 and 89 for the reception of balls 90 is mounted upon a sleeve 91 which is integral with the gear wheel 84. Springs 92 normally tend to force these balls into engagement with the inner periphery of the gear wheel 84. A screw 85 which is threaded into the outer end of the stub shaft 83 has an enlarged head which holds the gear wheel 84 in position and bears against a segmental gear wheel 93 which is connected by a pin 94 with the ratchet 86 and holds said segmental gear wheel and said ratchet in position. The gear wheel 84 meshes with an idler pinion 95 which is supported by the frame, said idler pinion in turn meshing with the pinion 55. An arm 96 which is carried by the cross head and moves vertically therewith, has a rack 97 formed thereon which meshes with the teeth 98 of the segmental gear 93. A finger 99 which is carried by the segmental gear, is adapted to contact with the resilient finger 100 as will be hereinafter described. This resilient finger 100 is mounted upon a brake 101, said brake being in turn pivoted upon a screw 102 which takes into the frame 6. A pin 103 limits the movement of this brake member in one direction, the face 104 of said member bearing against the ends of the teeth of the gear wheel 84 and limiting the movement of the brake member in the other direction. A set screw 105 is threaded through the extension 106 of the brake member, the lower end 107 of this set screw being adapted by striking upon the upper portion of the arm 96 to limit the upward movement

of said arm for a purpose which will be hereinafter described. A thumb piece 108 which is threaded upon the screw, forms a locking nut for locking said set screw against accidental movement after it has once been set.

The operation of the device is as follows: With the parts in the position illustrated in Fig. 1, the machine is placed upon the article, such as a letter to which the stamp is to be affixed. The operator then strikes a sharp blow upon the handle 10, depressing said handle against the tension of the spring 11 and consequently forcing the crosshead downward. During the initial downward movement of this cross head, the arm 96 turns the ratchet 86 forward without moving the gear wheel 84, through the rack 97 and the segmental gear wheel 93. After the ratchet has been turned forward the proper distance, the rack 97 moves out of engagement with the segmental gear wheel and said segmental gear wheel remains stationary during the further downward movement of the presser head 28. As this downward movement continues, the knife 17 coacting with the knife 59, cuts off the stamp which is to be affixed, said knife 17 yielding when its cutting edge comes into engagement with the beveled surface 61 of the knife 59, this yielding motion of the knife 17 causing said knife to be firmly pressed against the knife 59 at all times to secure an efficient shearing or cutting of the stamp. A set screw 109 limits the upward movement of the knife 17, a pin 110 passing through the lower end of the rod 9 and a boss 8' of the cross head to secure said parts together. When the handle 10 is released, the spring 11 forces said handle upwardly, the rack 97 again coming into mesh with the segmental gear wheel and turning the ratchet 86 to the right in Fig. 6. This causes the balls 96 to bind between the cut-away portions of the ratchet and the inner periphery of the gear wheel 86 and causes said gear wheel to turn with the ratchet. This movement of the gear wheel in turn imparts movement to the left to the idler pinion 95; imparts movement to the right to the pinion 55 and imparts movement to the left to the pinion 38. The feed roll 48 and the dampening or mucilaging roll 37 act to feed another stamp into position to be cut off by the knife, the roll 37 dampening or mucilaging the underside of the stamp as this is done. The receptacle 32 may contain either mucilage or water, in the first instance for use in connection with unmucilaged stamps and in the latter instance for use with mucilaged stamps, in accordance with the circumstances.

It will be seen by referring to Fig. 1 that as soon as the screw 105 limits the upward movement of the arm 96, it also limits the movement of the rack 97 and of the gear wheels and pinions. It accordingly limits the ex-

tent to which the web of stamps 57 shall be fed forward and provides means for adjusting this feed, for it may be desirable at times to use these machines in connection with other stamps than postage stamps and said stamps may vary in length and may accordingly be required to be fed forward differing distances.

It is necessary, since the movement of the handle in both directions is a very rapid one, to prevent the inertia of the parts from throwing either the gear wheel 84 or the segmental gear wheel 93 farther than is desirable and it is for this purpose that the spring finger 100 and the brake member 101 are provided. When in the upward movement of the arm 96, it contacts with the lower end 107 of the pin 105, it tends to lift said pin and does lift it for a very slight distance. In lifting this pin, however, it lifts the extension 106 of the brake member and rocks said brake member upon its pivot 102, which brings the face 104 of the brake member into engagement with the ends of the teeth of the gear wheel 84 and immediately brings said gear wheel to a stop and prevents it from being thrown farther around than its predetermined distance. Upon the downward movement of the arm 96, which is of course a very rapid one, the spring finger 100 serves to retard the movement of the segmental gear wheel 93 to prevent it from being thrown farther than is intended, for the finger 99 contacts with said spring finger at about the end of the movement of the segmental gear wheel.

When it is desired to remove the moistening or mucilage receptacle for the purpose of dampening the sponge, filling it with mucilage, or for any other reason, the set screw 34 is loosened and the receptacle is slid from the rear of the frame. The roller 48 may then be swung back to the position illustrated in Fig. 4. This brings the pins 53 over the outer ends of the members 45. By pressing downward upon the roller 48, these members 45 may be rocked upon their pivots to lift the cover plate 41 to thereby expose the interior of the receptacle. The sponge may then be removed or dampened as desired. Aside from these features, the interior of the receptacle and the associated parts are exposed so that ready access may be had thereto for cleansing purposes. In the cleansing operation it is simply necessary to hold the exposed parts under a faucet.

It will be readily apparent from the foregoing description that in packing the device for shipment the presser may be moved to its lowermost position and held in such position by any suitable means so as to reduce the size of the mechanism and the space occupied thereby.

The base 5 and side portions 6 of the frame are preferably made in one piece to reduce the expense of manufacture. The receptacle 32 and the rollers 37 and 48 are prefer-

ably made of non-corrosive metal such as phosphor bronze, to resist the action of the water and gum.

What we claim is,

- 5 1. In a stamp affixer, a reciprocatory plunger, a knife carried thereby, said knife being pivotally mounted, and adjusting means adapted to apply pressure to said knife in a direction longitudinally of the 10 path of movement of said plunger.
2. In a stamp affixer, a stamp magazine comprising a substantially cylindrical casing closed at one end, a rod or pintle disposed centrally of said casing and secured to said 15 closed end, a closure adapted to fit over the open end of said cylindrical casing, and key controlled locking means adapted to maintain said closure in place.
3. In a stamp affixer, a liquid reservoir, a 20 slotted plate pivoted thereto and a grooved roller having portions thereof extending within said slots, substantially as described.
4. In a stamp affixer, a liquid reservoir, a 25 roller disposed therein, a slotted plate pivotally mounted and disposed above said roller, and a feed roller mounted in a pivoted frame, said feed roller being adapted and arranged to feed stamps over said plate, and in contact with said first named roller.
- 30 5. In a stamp affixer, a reciprocatory plunger, a rack carried thereby, a segmental gear adapted to engage said rack during a portion only of its movement, and means to adjustably limit the movement of said rack 35 in one direction while the latter is in engagement with the said gear.
6. In a device of the character described, the combination with a supporting frame, of a moistening or mucilaging receptacle 40 movably mounted in said frame, feeding and dampening rolls mounted upon said receptacle and removable therewith, a vertically movable stamp pressing member, a knife carried by the moistening receptacle, and a 45 second knife carried by the stamp pressing member and adapted to co-act with the first named knife, the last named knife being yieldingly mounted with relation to the first named knife, and means for varying the tension of said knife.
7. In a device of the character described, the combination with a supporting frame, of a vertically movable stamp pressing mechanism, a moistening receptacle, feeding and 55 moistening rolls mounted upon said receptacle, a ratchet connection between said feeding and moistening rolls and the stamp pressing mechanism, and a brake mechanism for said ratchet mechanism adapted to be 60 thrown into operation upon the end of the upstroke of the stamp pressing mechanism.
8. In a device of the character described, the combination with a supporting frame, of a vertically movable stamp pressing mechanism, a moistening or mucilaging receptacle

cle, feeding and moistening rolls mounted upon said receptacle, a ratchet connection between said feeding and moistening rolls and the stamp pressing mechanism, and a 70 brake mechanism for said ratchet mechanism adapted to be thrown into operation at each end of the movement of the ratchet mechanism.

9. In a stamp affixer, a reciprocatory plunger, a rack carried thereby, a segmental gear 75 adapted to engage said rack during a portion only of its movement, a finger carried by said gear adapted to engage a suitable stop to check the movement of said gear when it is disengaged from said rack, a gear wheel connected with said segmental gear through the medium of a clutch, whereby said gear wheel is rotated only in one direction to feed and moistening rollers actuated by said gear wheel, substantially as described. 80

10. In a device of the character described, the combination with a stamp pressing mechanism, of a rack carried by said stamp pressing mechanism and movable therewith, said stamp mechanism reciprocating vertically, 90 means for normally holding said stamp pressing mechanism in an elevated position, feeding and moistening rolls having gear wheels connected thereto which mesh with each other, a gear wheel, gearing between said gear wheel and the feeding roll, a ratchet mechanism adapted to impart movement to said gear wheel in one direction, and a segmental gear connected to said ratchet mechanism with which said rack meshes, and a 100 set screw adapted to vary and limit the upward movement of the stamp pressing mechanism and consequently of the rack. 95

11. In a stamp affixer, a reciprocatory plunger, rotative means actuated by the 105 movement of said plunger to advance a stamp strip into the path of movement thereof, a brake adapted to positively check the movement of said rotative means and means carried by said plunger adapted to engage 110 said brake and throw it into braking relation with said rotative means upon the completion of the movement of said plunger in one direction.

12. In a stamp affixer, a reciprocatory plunger, a knife carried thereby, rotative means actuated by said plunger to advance a 115 stamp strip into the path of movement of said knife, and a friction brake actuated by said plunger and adapted to positively check the movement of said rotative means upon the completion of the movement of said plunger in one direction. 120

13. In a stamp affixer, a reciprocatory plunger, a knife carried thereby, rotative means actuated by said plunger to advance a 125 stamp strip into the path of movement of said knife upon the upward movement of said plunger, and a brake actuated by said plunger when it reaches the upward limit of 130

its path of movement, adapted to positively check the movement of said rotative means.

14. In a stamp affixer, a reciprocatory plunger, a rack carried thereby, a segmental gear adapted to engage such rack during a portion only of its movement, means operable by said gear to advance a stamp into the path of movement of said plunger, a spring stop and a finger carried by said segmental gear and adapted to engage said stop to prevent the rotation of said gear, in one direction, independently of said rack, substantially as described.

15. In a stamp affixer, a stamp magazine comprising a casing provided with a rod or

pintle to receive a roll of stamps rigidly supported by one end of said casing and a closure having an opening therein for the reception of said rod or pintle, said closure being adapted and arranged to fit over the said rod or pintle, and close the said magazine, substantially as described.

In testimony whereof we affix our signatures in presence of two witnesses.
